VENTILATED SHOE SOLE

Filed Feb. 21, 1929

FIG. 1.

FIG. 2.

FIG. 3.

4 Walter Crick
by Connally Bros. Mfg.

UNITED STATES PATENT OFFICE

WALTER CRICK, OF NORTHAMPTON, ENGLAND, ASSIGNOR TO FREVVA LIMITED, OF LONDON, ENGLAND, A CORPORATION OF GREAT BRITAIN

VENTILATED SHOE SOLE

Application filed February 21, 1929, Serial No. 341,808, and in Great Britain March 6, 1928.

This invention relates to boots and shoes, and concerns mainly, though not exclusively, those constructed with soles of water-proof material other than leather, e. g. rubber or 5 rubber composition and like mouldable substances suitable for the purpose.

The invention has particular reference to soles provided on the upper face thereof with 10 projections which form between them channels, grooves, or like passages through which air can flow for ventilating purposes, between the insole and the sole when the latter is applied to a boot or shoe.

The present invention has for its object the 15 provision of an improved sole of this kind as will be hereinafter described.

According to the invention there is provided, in or for a boot or shoe, a sole of the kind referred to, characterized by the provision of an additional projection located 20 around or partly around the projections aforesaid, and so formed as to make a watertight joint with the opposing part of the boot or shoe, when applied to the latter, said 25 projection being flexible so as to be self-adjusting to the boot or shoe.

By the phrase "self-adjusting to the boot or shoe" I mean that the said additional projection, by reason of its flexibility can readily 30 conform or adapt itself to the opposing part of the boot or shoe, viz. the insole, or the inseam or equivalent, or both of these parts, when the sole is applied to the boot or shoe, to make the watertight joint.

The additional projection located as aforesaid is formed to fit within the inseam or equivalent when the sole is applied to the boot or shoe, to render the latter more water-proof.

The expression "inseam or equivalent" is intended not only to include the inseam of a welted boot or shoe, but also any similar formation which may be found in boots or shoes made by other methods, such for example, as the lasted edges of the upper (and lining if provided) in a machine sewn boot or shoe. When the insole of the boot or shoe has a marginal or inside channel, as, for example, in welted work, said additional projection may also enter this channel. In any

case the projection is intended to make a watertight joint between the sole and the insole.

It is preferred to construct the additional projection so that it tends to bend or turn 55 over outwardly when subjected to pressure. In this way a particularly effective joint is made.

The said projection may be endless, or may 60 have a gap or opening therein to facilitate the formation of a joint with the shank of the boot or shoe, and the passage of air through the channels, grooves, or the like passages. More than one gap or opening may be provided in the projection if desired. Another 65 groove or channel may be formed between the additional projection and those within the same.

A series of radiating buttresses or like formations may be provided exteriorly of and 70 around the additional projection so as to prevent the latter from turning or bending over unduly as aforesaid. These buttresses or like supports also extend across and press into the inseam or equivalent, when the sole is applied to the boot or shoe bottom, and thus 75 tend to make the boot or shoe still more watertight, and also prevent the insole from "guttering" by supporting it. The said buttresses or like formations are preferably tapered 80 both longitudinally and transversely so as to enable them to accommodate or adjust themselves to the inseam or equivalent. By reason of this construction soles of the same 85 size may be applied to boots and shoes between which there are variations as regards the space formed by the inseam or equivalent, since the sole is to some extent rendered self-adjusting to the particular space in the boot or shoe bottom to which it is applied.

The sole formation hereinbefore described 90 may be applied to the forepart only but may extend wholly or in part through the waist and to the heel part if desired. For example 95 the ventilating formation may be confined to the forepart while the additional projection may be continued through the waist leaving the centre of the sole vacant for reception of the shank.

In the following, further description ref- 100

erence will be made to the accompanying drawing, wherein a sole constituting a convenient embodiment of the invention is illustrated.

5 In the drawing,

Figure 1 is a view of the upper or inner face of the sole.

Figure 2 is a transverse section taken along the line II—II of Figure 1.

10 Figure 3 is a transverse section of a welted shoe showing the sole applied thereto, and

Figure 4 is a longitudinal section of the forepart of such shoe.

According to the illustrative embodiment 15 of the invention, a sole 1, which may be made of rubber, rubber composition or other mouldable material of the kind hereinbefore mentioned, is provided centrally in the forepart 2 with a series of longitudinally disposed projections 3 which form between them corresponding grooves or channels 4. Partially surrounding the area formed by the projections 3 is a lip, rib or like projection 5 which extends higher than the projections 20 3, as shown in Figure 2. The lip or rib 5 is not continuous, i. e. it has a gap or opening 6 formed therein at the end adjacent to the waist portion of the sole, and, in addition, the corresponding ends of the projections 3 are bevelled or similarly formed i. e. at 3a, so that the formation of a joint with the shank 7 (Figure 4) of the boot or shoe is 25 facilitated. As illustrated in Figure 2, the lip or rib 5 may be slightly undercut exteriorly, i. e. at 5a, and formed at an angle or inclined 30 interiorly, i. e. at 5b, for a purpose hereinafter mentioned. Radiating buttresses 8, or like supports, which are tapered longitudinally and transversely, as shown in Figures 1 and 2, 35 are provided at suitable intervals round the outside of said lip or rib. If desired a groove or channel (not shown) may be provided between the projections 3 and the lip or rib 5, in communication with the grooves 4 and also 40 the gap 6 to further facilitate the flow of the air.

Referring to Figures 3 and 4, when the sole 1 is applied to a boot or shoe, the aforesaid central formation is located in the space 45 formed by the inseam 9 or equivalent and may thus replace the usual bottom filling where such would be otherwise provided. The rib or lip 5 fits within the inseam, and by reason of the aforesaid angularity or inclination turns outwards under pressure, as will 50 become evident by comparison between Figures 2 and 3. When the insole 10 has a channel 11 therein, the rib or lip 5 enters said channel and may or may not engage the 55 channel lip forming part of the inseam, while the buttresses 8 or like supports press into or against and adapt themselves transversely to the inseam or equivalent, as represented in Figures 3 and 4, as and for the purpose 60 previously alluded to herein, and also af-

ford support to the lip or rib 5. Thus when the boot or shoe is in wear a free flow of air between the insole and sole is engendered by the pumping action set up by the flexing of the sole and by the alternate application and relief of the pressure of the foot thereon, the boot or shoe thus being effectually ventilated interiorly by passage of air through the usual small tack holes which are present in the insole. The insole may 70 be purched to permit passage of air but it is found that the small holes generally left in the insole when the tacks are employed to tack the insole upon the last during manufacture, are withdrawn, act as ventilation holes to permit an air change to be effected in the interior of the boot or shoe due to the movement of walking.

What I claim then is:—

1. A boot or shoe sole provided on the upper face thereof with projections which form between them passages through which air can flow for ventilating purposes, and an additional marginal, upstanding projection formed to fit within the inseam or equivalent, 90 when the sole is applied to the boot or shoe, to render the latter more waterproof.

2. A boot or shoe sole provided on the upper face thereof with projections which form between them passages through which air can flow for ventilating purposes, and an additional marginal projection which is formed higher than the projections aforesaid and makes a watertight joint with the opposing part of the boot or shoe, when the sole is applied thereto.

3. A boot or shoe sole provided on the upper face thereof with projections which form between them passages through which air can flow for ventilating purposes, an additional marginal projection so formed as to make a watertight joint with the opposing part of the boot or shoe, when applied to the latter, and buttresses extending outwards from the additional projection.

4. A boot or shoe sole provided on the upper face thereof with projections which form between them passages through which air can flow for ventilating purposes, and an additional marginal, upstanding projection formed to fit within the inseam or equivalent, 115 when the sole is applied to the boot or shoe, to render the latter more waterproof, said projection being flexible so as to be self-adjusting to the boot or shoe.

5. A boot or shoe sole provided on the upper face thereof with projections which form between them passages through which air can flow for ventilating purposes, and an additional marginal projection which is formed higher than the projections aforesaid and makes a watertight joint with the opposing part of the boot or shoe, when applied to the latter, said projection being flexible so as to be self-adjusting to the boot or shoe.

6. A boot or shoe sole provided on the upper face thereof with projections which form between them passages through which air can flow for ventilating purposes, and an additional marginal projection so formed that it fits within the inseam or equivalent and tends to bend over outwardly under pressure when the sole is applied to the boot or shoe, to render the latter more waterproof. 70
- 10 7. A boot or shoe sole provided on the upper face thereof with projections which form between them passages through which air can flow for ventilating purposes, and an additional marginal projection which is so formed that it extends higher than the projections aforesaid, and fits within the inseam or equivalent, when the sole is applied to the boot or shoe, to render the latter more waterproof. 75
- 15 8. A boot or shoe sole provided on the upper face thereof with projections which form between them passages through which air can flow for ventilating purposes, and an additional marginal projection which is so formed that it extends higher than the projections aforesaid, and tends to bend over outwardly under pressure to make a watertight joint with the opposing part of the boot or shoe, when the sole is applied thereto. 80
- 20 9. A boot or shoe sole provided on the upper face thereof with projections which form between them passages through which air can flow for ventilating purposes, and an additional marginal projection which is so formed that it extends higher than the projections aforesaid, and fits within the inseam or equivalent, when the sole is applied to the boot or shoe, to render the latter more waterproof, said projection also being flexible so as to be self-adjusting to the boot or shoe. 85
- 25 10. A boot or shoe sole provided on the upper face thereof with projections which form between them passages through which air can flow for ventilating purposes, and an additional marginal projection which extends higher than the projections aforesaid, and is so formed that it fits within the inseam or equivalent and tends to bend outwardly under pressure, when the sole is applied to the boot or shoe, for the purpose set forth. 90
- 30 11. A boot or shoe sole provided on the upper face thereof with projections which form between them passages through which air can flow for ventilating purposes, an additional marginal projection so formed as to make a watertight joint with the opposing part of the boot or shoe, when applied to the latter, said projection being flexible, so as to be self-adjusting to the boot or shoe, and buttresses extending outwards from the marginal projection. 95
- 35 12. A boot or shoe sole provided on the upper face thereof with projections which form between them passages through which air can flow for ventilating purposes, an additional marginal projection formed to fit within the inseam or equivalent, when the sole is applied to the boot or shoe, and buttresses extending outwards from the marginal projection, for the purpose set forth. 100
- 40 13. A boot or shoe sole provided on the upper face thereof with projections which form between them passages through which air can flow for ventilating purposes, an additional marginal projection formed so that it tends to bend over outwardly under pressure, when the sole is applied to the boot or shoe, and buttresses extending outwards from said projection, for the purpose set forth. 105
- 45 14. A boot or shoe sole provided on the upper face thereof with projections which form between them passages through which air can flow for ventilating purposes, an additional marginal projection formed to fit within the inseam or equivalent, when the sole is applied to the boot or shoe, said projection being flexible, and buttresses extending outwards from the projection, all for the purpose set forth. 110
- 50 15. A boot or shoe sole made of mouldable pliable material having moulded thereon a series of projections which form between them passages through which air can flow for ventilating purposes, a marginal rib formed to make a watertight joint with the opposing part of the boot or shoe, when applied to the latter, and tapered buttresses radiating outwards from the rib. 115
- 55 16. A boot or shoe sole made of mouldable pliable material having moulded in the forepart thereof a series of projections which form between them passages through which air can flow for ventilating purposes, a marginal upwardly tapered rib formed higher than and substantially around the projections aforesaid so as to fit within the inseam or equivalent, when the sole is applied to the boot or shoe, and buttresses radiating outwards from said rib and tapered both longitudinally and transversely, all for the purpose set forth. 120
- 60 In testimony whereof I affix my signature.
